ELECTRIC SWITCH DEVICES

Eric Clifton Wahlberg, Stamford, Conn., assignor
to Electrolux Corporation, New York, N. Y., a
corporation of Delaware

Application July 16, 1942, Serial No. 451,111

9 Claims. (Cl. 200—97)

This invention relates to an improved electric switching device, and more particularly to a switch having a plurality of positions and including means for automatically retaining the switch in at least one of such positions for a comparatively short though appreciable length of time.

More specifically, the invention relates to a snap-action switch having two terminal positions and an intermediate position. A switch of this nature includes means for rapidly throwing the switch from one terminal position to the other when a switch handle is actuated. In accordance with the invention, means are provided for automatically interrupting in an intermediate position the throw of the switch which has been initiated by actuating the handle. The switch is held in this intermediate position for a short interval and is then automatically released to continue to travel to the other terminal position without further manipulation by the operator.

While a switch having these general characteristics may find wide application in the electrical art, the particular switch herein shown and described is especially suited for controlling in a simple manner the operation of the system including a plurality of electric motors shown and described in applicant's copending application Serial No. 428,018 filed January 24, 1942.

An object of the invention is to provide an improved switch of the above type in which the length of time that the switch is held in its intermediate position may be easily and accurately determined and adjusted.

Another object of the invention is to provide a switch of this type having the switch means removed from the means for stopping the switch in its intermediate position so that the two means will not interfere with one another.

A further object of the invention is to make a switch that is compact in construction and that is easy to manufacture, and that is less likely to get out of order than other switches of the same type.

A further object of the invention is to provide a three pole switch having its contacts so arranged that a misalignment of one set of its contacts will not cause it to fail to engage one of the other sets of contacts. This is accomplished by means of resilient contacts which are more easily used in a switch of the construction set forth than in other types of three pole switches. Such an arrangement is particularly desirable when used in the combination set forth for if the switch should at any time fail to make

proper contact so that one of the circuits was not closed at the proper time, loss of synchronism of the motors controlled thereby might result.

Another object of the invention is to provide a three position switch with time delay means for holding the switch in its mid-position when actuated from one terminal position toward the other in which the time delay will be the same, regardless of the direction in which the switch is actuated.

Still another object of the invention is to provide a three position switch of the type before mentioned in which the time delay means for determining the time during which the switch is held in its mid-position is independent of the means for holding the switch in its mid-position so that the action of the last mentioned means may be quick and positive and so that this means may be made compact and of small size.

20 A further object of the invention is to arrange the spring of a snap-action switch of the type mentioned so that the action of the snap-action spring does not tend to cause the switch elements to become misaligned when the switch is stopped intermediate its terminal positions.

25 A still further object of the invention is to provide in a switch of the type mentioned a thermal relay for determining the time during which the switch is held in mid-position.

30 Another object of the invention is to provide such a switch which may satisfactorily be used in aircraft. To this end, it is an object of the invention to provide such a switch that will operate satisfactorily regardless of the position in which it is held. To the same end, it is another object to provide a switch of this type, using a thermal relay that shall be unaffected by changes in ambient temperature such as may be experienced if the device is near the motor of the aircraft or if the aircraft is adapted to fly at high altitudes at which the temperature may be low.

35 Further objects and advantages of the invention will be apparent from the following description considered in connection with the accompanying drawings, which form a part of this specification and in which:

Fig. 1 is a side elevation showing a switching device in accordance with the invention;

40 Fig. 2 is a vertical section on an enlarged scale 50 through the device shown in Fig. 1;

Fig. 3 is a horizontal section taken on the line 3—3 of Fig. 2;

Fig. 4 is a view on a still larger scale of a section taken on the line 4—4 of Fig. 2;

Fig. 5 is a view on a somewhat smaller scale

of a section taken on the line 5—5 of Fig. 4; Fig. 6 is a plan view of a portion of the device shown in Fig. 4;

Fig. 7 is a section taken on the line 7—7 of Fig. 4;

Fig. 8 is a view similar to Fig. 5 showing a modified form of a portion of the device;

Fig. 9 is a section taken on the line 9—9 of Fig. 8; and

Fig. 10 is a wiring diagram illustrating the manner of connecting a switch in accordance with the invention, in an electrical system of the type described in applicant's above-mentioned copending application.

Referring to Figs. 1 and 2, the switching device comprises a manually operated switch designated generally by the reference numeral 1, a thermal relay designated by the reference numeral 2, and an electromagnet designated by the reference numeral 3.

Referring now to Figs. 2 and 3, the manually operated switch is seen to comprise a switch arm 4 composed of some non-conducting material which is pivotally mounted at 5. A spring 6 connects the switch arm 4 with an operating lever 7 which is also pivoted at 5. Through the switch arm pass rods 8, 9, and 10 adapted to connect the switch contacts on opposite sides of the switch when the switch is moved to one of its closed positions. In the position shown in Fig. 2, the switch arm 4 is in a position in which the members 8, 9, and 10 do not make contact with any of the fixed contacts of the switch and the switch is thus in open position. Fixed at one side of the switch 1 there are contacts 11, 12, 14, 15, and 17. The contacts 8, 9, and 10 of the switch arm 4 are adapted to engage contacts 14, 11, and 17 when the switch is in mid-position and the contacts 15, 12, and 17 when the switch is in its other terminal position. The contact 17 comprises an arcuate strap which is in continuous engagement with the contact 10 when the switch is moved from its mid-position to the other terminal position so that the circuit connected thereto is not broken during motion of the switch from mid-position to the second terminal position. On the other side of the switch there are fixed contacts 16, 13, and 18, each of which comprises an arcuate strap similar to contact 17 and so located as to make contact with the members 8, 9, 10 when the switch arm 4 is in either its mid-position or its second terminal position or any position therebetween.

The contacts 11 through 18 are made of a springy material so that they may be depressed by the moving contacts 8, 9, 10 to a sufficient extent to provide a good wiping contact therewith. Since the contacts are made of resilient material, even if they should be slightly out of alignment, good contact will be made with all three members 8, 9, and 10.

As best seen in Fig. 2, the spring 6 tends to pull the switch arm 4 and the operating lever 7 together. Movement of the operating lever 7 in either direction about the pivot 5 is limited by means of the stop 91 which engages the casing 92 of the switch. Likewise, movement of the switch arm 4 is limited by engagement of projection 27 with either of the stop abutments 28 or 29. If the operating lever 7 is moved from the position shown in Fig. 2 to its opposite limiting position, the switch arm 4 remains in the position shown until the spring 6 passes over the pivot 5, at which time the switch arm 4 suddenly snaps toward its opposite terminal position. In the

switching device shown there is a pin 30 projecting through the casing 92 into the path of the projection 27 on the end of the switch arm 4. This pin 30 stops the switch arm 4 in mid-position and prevents further movement of the switch arm toward its second terminal position until the pin 30 is withdrawn from engagement with the projection 27. Likewise, when the operating lever 7 is moved back in the other direction towards the position shown in Fig. 2, the pin 30 again arrests the motion of the switch arm 4 in mid-position until the pin 30 is withdrawn.

The pin 30 is actuated by the electro-magnet 3. As shown in Fig. 2, the pin 30 is mounted on the end of a rod 31 which is in threaded engagement with the armature 32 which is reciprocable within the solenoid 37. The distance that the pin 30 projects from the armature 32 can be adjusted by turning the rod 31 which can be held in adjusted position by means of lock nut 33. The armature 32 is spring-biased outwardly from the solenoid 37 in such a manner as to force the pin 30 into a position in which it lies in the path of the projection 27. The exact limit of the inward motion of the pin 30 is determined by the position of the stop nut 35 which is also threaded on the rod 31. Inward motion of the armature 32 toward the solenoid 37 is limited by means of a stop bolt 36 which is screwed into core 93 of the solenoid 37. When the stop bolt 36 has been adjusted to the desired position, it may be locked in that position by means of nut 95.

As shown in Fig. 2, the thermal relay 2 is mounted on top of the electro-magnet 3. The construction of thermal relay 2 is shown in detail in Figs. 4 through 7. The relay actuates a switch arm 40 to close a circuit between the fixed contacts 38 and 39. As seen best in Fig. 5, the switch arm 40 is secured to the base of a U-shaped member having two resilient metal legs 41 and 42 which are fixed to the base of the relay casing at 43 and 44. The switch arm 40 is moved between opened and closed position by means of a spring 45 which in turn is controlled by means of a second U shaped member 46 which is secured to or integral with the ends of resilient legs 41 and 42 beyond the fixed points 43 and 44. The ends of the spring 45 are somewhat compressed and tend to push the switch arm 40 as far as possible from the member 46. Thus, if the member 46 is moved up and down in accordance with the position of the bolt 47 connected thereto, the switch arm 40 moves in an opposite direction.

Due to the position of the parts, the expansive force of the spring 45 does not act to move the switch arm 40 until the member 46 has moved slightly past a position of alignment with the legs 41 and 42.

For this reason, the switch arm 40 moves from open to closed position with a snap action. The upward movement of the switch arm 40 is limited by means of an adjustable stop 94. The bolt 47 actuating the member 46 is threaded to an insulating block 48 which is supported by a pair of bi-metallic strips 49 and 50. (See Fig. 6.) The other ends of the bi-metallic strips are attached to a member 51 of some material that is an electric insulator. Pins 52 and 53 serve the dual function of supporting the member 51 on the ears 54 and 60 of terminals 59 and 61 and forming an electrical connection between the bi-metallic strips 49 and 50 and the corresponding ears 54 and 60. The bi-metallic strips are electrically connected together by means of a resistance grid

56 62 which is connected at one end to the bi-metal

49 by the pin 63 and at the other end to bi-metal 50 by means of pin 64. A sheet of mica or other electrical insulator is placed between the grid 62 and the bi-metals 49 and 50 to prevent them from short-circuiting one another.

The operation of the above-described thermal relay is as follows: If electrical power is connected to the terminals 59 and 61, it will flow through the bi-metals 49 and 50 and the resistance grid 62 in series. The heat generated thereby will cause the bi-metals to bend in such a manner as to lift the bolt 47 which in turn lifts the member 46. As soon as the member 46 passes the plane defined by the straps 41 and 42, the spring 45 will with a snap action move the switch arm 40 downward and close the circuit between the fixed contacts 38 and 39.

In Figs. 8 and 9 there is shown a modification of the thermal relay illustrated in Figs. 4 through 7. The switch member 40 is actuated by member 46 exactly as in the first described embodiment. The insulating block 48a is moved up and down by means of bi-metallic strips in exactly the same manner as member 48 in the first embodiment. However, the member 48a is not mounted above the member 46 as in the previously described embodiment but is instead mounted in the same plane therewith. The member 48a is connected to the member 46 by means of a long tongue 70 having a forked end 71. The member 70 is preferably made of bi-metallic material and the bi-metallic elements thereof are reversed with respect to the position of the bi-metallic elements 49 and 50. With this arrangement the position of the fork 71 may be made to be independent of the ambient temperature, for any movement of the member 48a caused by response of bi-metals 49 and 50 to changes in ambient temperature will be exactly offset by an opposite movement of the bi-metal 70. Bi-metal 70, however, is thermally as well as electrically insulated from bi-metals 49 and 50 by the member 48a, so that when current is passed through bi-metals 49 and 50 and the grid 62, the thermal relay will operate in the manner of the first-described relay. Since the lever arm provided by bi-metal 71 increases the magnitude of the movement of member 46 in response to bending of bi-metals 49 and 50, the thermal relay in this embodiment will be more sensitive than the relay first described.

Referring to Fig. 10, there is shown the scheme of connections between the manually operated switch 1, the thermal relay 2, and the electro-magnet 3. There is also shown a manner of connecting the entire switching device to a circuit for controlling the operation of synchronously operating direct current motors. It will be understood, however, that the same switching device may be used in other connections. Reference numerals 84 and 85 designate a source of direct current power which is connected by leads 19 and 21 to fixed contacts 18 and 16 of the manual switch 1. A group of direct current motors 81, 82, and 83 are connected by leads 24, 25, and 26 to the fixed contacts 17, 12, and 15 of the manual switch 1. When the manual switch is in its second terminal position designated by III, the source of power is connected to the brushes of the motors. This circuit may be traced from power terminal 84 through lead 21, contacts 16 and 15 and lead 26 to one group of brushes, thence through the armatures of the motors and back from the other set of brushes through lead 25 and contacts 12 and 13 to lead

5 20. Lead 20 is connected to ground and likewise the motor fields are connected at one side to ground. The other side of the motor fields, which are connected in parallel, is connected to lead 24. From lead 24 the circuit proceeds through contacts 17 and 18 and lead 19 back to the other side of the power source at terminal 85. There is a three phase connection 86 connecting slip rings 87, 88, and 89 of the motors 81 through 83. The slip rings are connected to fixed taps taken from the armatures of the motors at intervals of roughly 120 degrees. The three phase connection 86 serves to maintain the motors in synchronism as more fully set forth in my above-mentioned copending application. Two of the leads forming the three phase tie between the motors are also connected by means of leads 22 and 23 to fixed contacts 11 and 14 of the manual switch 1. When the manual switch is in its mid-position designated by II and IV, the source of electric power energizes the fields of the motors as before in position III from terminal 85 through lead 19, contacts 18 and 17 and lead 24 through the fields to ground. The brushes of the motors are not connected, however, and instead the ground lead 20 connects the source of power through contacts 13 and 11 to lead 22 and thence through one set of slip rings and a portion of the armature of each of the motors and out through another set of slip rings back to lead 23, contacts 14 and 16, lead 21 to terminal 84 at the other side of the direct current source of power. As set forth in my copending application, this connection of the motors serves to cause their armatures to assume definite positions of alignment with respect to their fields.

When the switch is in position II, IV, the thermal relay 2 is also energized from the direct current source of power. This circuit may be traced from terminal 84 through lead 21, contacts 16 and 14, lead 23, lead 55, bi-metal 49, grid 62, bi-metal 50, lead 58, lead 22, contacts 11 and 13, and thence from lead 20 through ground to the field circuits and back through lead 24 through contacts 17 and 18 and lead 19 to terminal 85. Thus, when the switch 1 is moved from its open position corresponding to I to the mid-position II, the synchronous motors are first brought into alignment. Then after a definite time, depending upon the constants of the circuits, thermal relay 2 is actuated to close its contacts 39 and 38 through switch member 40. This causes energization of electro-magnet 3 in parallel with thermal relay 2 from the leads 22 and 23. When electro-magnet 3 is energized, its armature moves inwardly towards its solenoid, retracting pin 30 and allowing switch arm 4 of manual switch 1 to move to its second terminal position designated by III. The motors then start up and operate synchronously as long as the manual switch is left in this position.

When the manual switch is in position III, the thermal relay 2 and the electro-magnet 3 are both de-energized so that the armature 32 of electro-magnet 3 is forced outwardly from solenoid 31 by spring 34, thus projecting pin 30 into the path of the projection 37 on the end of switch arm 4 of the manual switch 1.

When it is desired to stop the motors, the operating lever 7 of the manual switch 1 is moved into its opposite position which tends to move switch arm 4 to its open position. However, the pin 30 holds the switch arm 4 in mid-position designated in Fig. 10 by IV. In this position the brushes of the motors are disconnected from the

power source and direct current is applied to two taps on the armature of each motor through a pair of slip rings as in position II. This application of direct current to fixed taps on the armature of each of the motors causes them to be quickly brought to a stop. Since the motors are still connected by means of the three phase connection 86, they decelerate in synchronism. When the motors finally come to rest, they are all brought into alignment with one another as described before when the switch was moved from position I to position II.

While the motors are decelerating and coming to rest, the thermal relay 2 is again energized and after a definite time closes the circuit through the electro-magnet 3 which, as above described, withdraws pin 30 from the path of projection 27 on the switch arm 4 and allows it to snap into its open position as shown in Fig. 2.

If it is desired to change the length of time during which the manual switch is held in mid-position, this can easily be accomplished by varying the position of bolt 47 in member 48 of the thermal relay 2. The thermal relay may also be adjusted by adjusting the position of stop 94. If a variable resistance is inserted in series with the actuating elements of the relay as at 96, the time delay of the relay may be adjusted electrically. It is to be noted that time delay between energization of the thermal relay and the closing of its contacts is independent of the direction of movement of the manual switch into its mid-position.

Since a separate relay has been used to determine the time during which the manual switch is held in its mid-position, the electro-magnet actuating the stop pin 30 may be made quick acting and compact and its operation can be made to be independent of its position. Because the spring 34 exerts a greater force than the weight of the armature 32, the armature will not move except under the action of the solenoid even when the electro-magnet is turned so that the weight of the armature tends to move it inwardly. Likewise, the solenoid is made strong enough to draw in the armature even though the electro-magnet is in such a position that the weight of the armature is added to the bias of the spring 34 tending to force the armature outwardly.

Since the time delay mechanism is of the thermal type rather than the mechanical dashpot type, the time delay is also independent of the position of the switching device. The moving elements of the thermal relay are all of light weight compared with the actuating forces of the spring and the bi-metals.

The manual switch itself, being always spring-biased toward one position or the other by a spring having a force large compared with the weights of the moving parts of the switch, is also independent of position as far as its operation is concerned.

Since the spring of the snap action manual switch is always in tension, it holds the moving elements together even though the switch is arrested in mid-position. This is an advantage over known switches of this type in which the spring was in compression, serving to bias the switch arm against the fixed contacts as well as to move the switch. With the previous form of switch, the parts were apt to become cocked at an angle when arrested in mid-position.

Since the contacts of the manual switch are mounted on either side thereof, the end of the

switch arm is left free for cooperation with the stop pin. Of course the position of the stop pin and contacts could be interchanged, the important thing being to separate them so as not to interfere with one another.

It will thus be seen that there is provided by the invention a switching device fulfilling all of the objects set forth at the beginning of the specification. While two preferred embodiments 10 of the invention have been described, it is obvious that many modifications therein might be made by one skilled in the art and it is intended to cover by these Letters Patent all forms of the invention falling within the spirit and scope of 15 the appended claims.

I claim:

1. A pivoted switch arm, a plurality of conducting members supported on said arm at right angles to the plane of movement thereof and 20 spaced radially from one another, stop means for limiting rotation of the switch between two end positions, a spring biasing the switch arm into the nearest end position, an abutment on the end of the switch arm, stop means spring-biased into 25 a position projecting into the path of the switch arm at a point midway between the end positions where it will engage said abutment when the switch arm is actuated from one end position toward another to prevent further movement to 30 said other end position, and means for withdrawing said stop means.

2. A switching device comprising a manual switch having a switch arm rotatable between two extreme positions, an electro-magnet mounted 35 on the manual switch having a solenoid lying in the plane of movement of said switch arm and having an armature movable along an axis passing through the center of rotation of said switch arm, a projection on the end of the armature 40 lying in the path of the switch arm when the armature is in extended position, means to bias the armature to its extended position, and time delay means set in operation by the manual switch when held in mid-position by said projection for energizing said solenoid after an appreciable time, said solenoid when energized being adapted to overcome said biasing means and 45 retract the armature to such an extent that the projection no longer lies in the path of the switch arm.

3. A three position switch including a switch arm having two terminal positions and a mid-position, manual means for initiating movement of the arm from one terminal position toward another, means for arresting the switch in mid-position, thermal means energized when the switch is in mid-position for releasing said arresting means after the switch has been in said mid-position a definite period of time, said period 55 being the same regardless of the direction from which said switch reaches the mid-position, and means for continuing said movement of the arm to said other position after release of the arresting means.

4. A three position switch, means for moving the switch from an end position to a middle position, means tending to cause the switch when in a middle position to move to an end position opposite to that which it last occupied, means for preventing movement of the switch past the middle position until a definite time after it has been moved from an end position, and thermal means set into operation when the switch is in a mid-position for releasing said movement preventing means.

5. A synchronous motor controller comprising a three position switch including a switch arm having two terminal positions and a mid-position, means for initiating movement of said arm from one terminal position towards the other terminal position, relay means controlling a lock for interrupting said movement of switch arm and temporarily holding the latter in its mid-position, thermal means controlling the time during which the switch is locked in mid-position, temperature responsive means for compensating said thermal means for changes in ambient temperature so as to maintain constant the period of time during which the switch is locked in mid-position, and means for continuing said movement to said other position upon release of said lock.

6. A motor controller adapted for use on aircraft comprising a manual snap action switch having a spring for producing the snap action, an electro-magnet actuating a lock for holding the switch in a position midway between its end positions, said electro-magnet having a solenoid and an armature therefor and a spring biasing the armature outwardly from the solenoid into switch locking position, said snap action spring and said biasing spring and said solenoid being strong enough compared to the weight of the parts actuated thereby to perform their functions in their normal manner regardless of the position of the controller relative to the earth.

7. A three position switch, means for moving the switch from an end position to a middle position, means tending to cause the switch when in a middle position to move to an end position opposite to that which it last occupied, means for preventing movement of the switch past the middle position until a definite time after it has been

moved from an end position, thermal means set into operation when the switch is in a mid-position for releasing said movement preventing means, said thermal means comprising a bimetallic strip which is heated by electric current when the switch is in the middle position.

8. A three position switch, means for moving the switch from an end position to a middle position, means tending to cause the switch when in a middle position to move to an end position opposite to that which it last occupied, means for preventing movement of the switch past the middle position until a definite time after it has been moved from an end position, thermal means set into operation when the switch is in a mid-position for releasing said movement preventing means, said thermal means comprising a bimetallic strip which is heated by electric current when the switch is in the middle position and a second bimetallic strip connected to the first bimetallic strip but thermally insulated therefrom and mounted with its component metal parts reversed with respect to said first bimetallic strip.

9. A three position switch having an open circuit position, a conditioning circuit position, and a closed circuit position, snap action means for moving said switch between open and closed circuit position, spring means for holding the switch in conditioning position for a predetermined time whenever the switch is moved between open and closed positions, magnetic means for overpowering said spring means, thermo-electric means for setting into action said magnetic means, and switch contacts closed by said switch in its conditioning position completing a circuit to said thermo-electric means.

ERIC CLIFTON WAHLBERG.
